CLAIM

The ornamental design for a flip chip on glass (FCOG) image sensor, as shown and described.

DESCRIPTION

FIG. 1 is a perspective view of a flip chip on glass (FCOG) image sensor showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plain view thereof; and,

FIG. 7 is a bottom plain view thereof.
